Norwood, Mass., assignors to Epsco, Incorporated, Bos-
ton, Mass., a corporation of Massachusetts

Application May 10, 1957, Serial No. 46,099

Term of patent 14 years

(Cl. D26—5)

FIG. 1

FIG. 2

FIG. 3

Fig. 1 is a perspective view of an electromagnetic output indicator for data processing apparatus or similar article, showing our new design;

Fig. 2 is an opposite perspective view; and

Fig. 3 is a fragmentary front elevational view thereof. The essential features of our new design reside in the portions shown in solid lines in the drawing. The broken line showing of legible matter in the drawing is for illustrative purposes only. A portion of the drawing figures is diagonally lined to indicate transparency.

We claim:

The ornamental design for an electromagnetic output indicator for data processing apparatus or similar article, substantially as shown and described.
